UNITED STATES PATENT OFFICE.

CARL HOLSTEIN, OF CHICAGO, ILLINOIS.

DESIGN FOR A CHAIR.

SPECIFICATION forming part of **Design No. 25,197**, dated **February 25, 1896**.

Application filed December 23, 1895. Serial No. 573,163. Term of patent 31 years.

To all whom it may concern:

Be it known that I, CARL HOLSTEIN, a citizen of the United States, residing at Chicago, Cook county, State of Illinois, have invented 5 and produced a new and original Design for Chairs, of which the following is a specification, reference being had to the accompanying drawing, forming a part of this specification.

The accompanying drawing shows a perspective view of a rocking-chair, illustrating my design.

The leading feature of my design is that portion constituting the side of the chair.

Each of the side portions of the chair are 15 alike, and each of these side portions is shown as formed of a solid piece having its edges cut with ornamental curves, and to the outer face of each of the side portions suitable ornamental molding may be applied.

20 The arms of the chair are shown as attached to the upper edges of the side portions, and the rockers of the chair are attached to the bottoms of the side portions. At the back of the

side portions extend the uprights to which the back of the chair is attached. 25

The seat of the chair will extend between the side portions, to which it will be connected.

The back of the chair is shown as extended from side to side, and the edges of the back are cut upon substantially the lines shown. At 30 the top corners of the back open-work ornaments are formed, and, if desired, the piece from which the back is formed may be cut in ornamental outline adjacent the upper corners. On the face of the back, at the points 35 shown, ornamental molding or carving may be formed.

Having thus described my invention, what I claim, and desire to secure by Letters Patent, is—

40 The design for a chair, substantially as shown and described.

CARL HOLSTEIN.
